UNITED STATES PATENT OFFICE

142,690

DESIGN FOR A BROOCH PIN OR SIMILAR ARTICLE

Frederick Bieberbach, New York, N. Y., assignor to Nordic Silver Co., Inc., New York, N. Y.

Application June 18, 1945, Serial No. 120,182

Term of patent 3½ years

(Cl. D45—19)

To all whom it may concern:

Be it known that I, Frederick Bieberbach, a citizen of the United States, residing at New York city, in the county and State of New York, have invented a new, original, and ornamental Design for a Brooch Pin or Similar Article, of which the following is a specification, reference being had to the accompanying drawing, forming part thereof.

Fig. 1 is a plan view of a brooch pin or similar article, showing my new design.

Fig. 2 is a side view thereof.

The dominant feature of the design resides in the portions shown in full lines.

I claim:

The ornamental design for a brooch pin or similar article, substantially as shown and described.

FREDERICK BIEBERBACH.
